UNITED STATES PATENT OFFICE.

ANDREW NIEMI, OF HANCOCK, MICHIGAN.

HIGH SHOE.

Application filed April 23, 1926. Serial No. 104,124.

The invention relates to improvements in shoes of the type in which the upper is provided with an upwardly extending leg portion split down its front coincident with the 5 split along the instep portion, a lacing and the ordinary eyes or other fasteners being employed to close the split. The invention also relates to shoes of this type in which a flap is carried by one side of the leg portion 10 to extend in front of the lacing and lap onto the other side of the leg, giving a very desirable and neat shoe for any outdoor use, particularly for military purposes, hunting, fishing, etc.

15 It is the object of the invention to improve upon shoes of the above described nature, by providing novel elastic means for securing the flap in closed position and holding it snugly in place whether the split of 20 the leg portion of the upper be entirely or only partially closed by the lacing.

With the foregoing in view the invention resides in the novel subject matter described and claimed, the description being supplemented by the accompanying drawings.

Fig. 1 is a perspective view of a shoe constructed in accordance with my invention.

Fig. 2 is an exaggerated horizontal sectional view showing the flap secured closed.

30 Fig. 3 is a detail elevation showing an instrument which is preferably used to apply and release the fastening means of the flap.

In the drawings above briefly described, the numeral 4 designates the upper of the 35 shoe, said upper having an upward extension or leg portion 5 which is split down in front as at 6, coincident with the usual split 7 over the instep portion of the upper. Along the edges of the split 6-7 eyelets 8 40 have been shown, with which a lacing 9 is engaged in the usual or any preferred manner. One side of the leg portion 5 is provided with a flap 10 to extend in front of the lacing and the eyelets, and novel provision is made for holding the flap in closed 45 position.

The part of the leg portion 5, overlapped by the flap 10, is provided with a plurality of vertically spaced eyelets 11 through 50 which elastic straps 12 pass from the interior to the exterior of the shoe, the inner ends of these straps being preferably skived or tapered to feather edges as indicated at 13, and cemented or otherwise secured to the 55 leg portion 5. The outer ends of these straps are provided with metallic loops 14 for en-

gagement with hooks 15 which are secured to the inner side of the flap 10, and it will be understood that in order to interengage the fasteners 14 and 15, it is necessary to 60 stretch the elastic 12 to some extent, so that the resiliency of the straps will then act to snugly hold the flap in closed position. Each loop 14 is vertically elongated and is 65 of a length greater than the diameter of the openings 11 in the shoe leg to prevent the drawing into the shoe through said openings of the loops 14. Each of the loops has one of its vertical sides engaged with the strap 12, whereas its other side is outwardly 70 bowed as at 16 to engage the hook 15. For the purpose of stretching the straps, incident to fastening or releasing the coacting fasteners 14-15, an instrument such as that shown in Fig. 3 is preferably used. This instrument preferably comprises a substantially flat shank 17 having a pair of projecting spurs 18 at one end, said spurs being spaced apart a distance greater than the vertical width of the outwardly bowed 80 fastener portion 16, so that these spurs will engage the ends of the loop 14, as shown in Fig. 3, leaving ample space for the hook 15 to enter or leave the portion 16.

By employing the construction shown and 85 described, a shoe is produced which will be very desirable for outdoor purposes in general but is particularly advantageous for any rough outdoor work, and it will be seen that when the flap is snugly held closed, the 90 general appearance given at the front, is that of a puttee overlapping the upper end of an ordinary high shoe.

In the preferred form of construction, the leg portion 5 is provided with a relatively 95 narrow side along which one row of the fasteners 8 is disposed, and with a relatively wide side whose front portion forms the flap 10, the other row of fasteners 8 being then carried by a separate strip 19 which is 100 stitched at 20 or otherwise secured to the inner surface of the wide side of the leg.

As excellent results are obtainable from the general construction herein disclosed, it is preferably followed. However, within 105 the scope of the invention as claimed, variations may be made.

I claim:

In a shoe of the type having a leg portion 110 a front split opening through the upper end of said leg portion, lacing for closing the split, and a flap on one side of the leg por-

tion adapted to overlap the other side of said leg portion; a vertical row of fasteners on the inner side of said flap, additional fasteners cooperable with the first named fasteners, and elastic straps disposed horizontally and carrying said additional fasteners, said leg portion of the shoe having openings through which said elastic straps pass, the

inner ends of said straps being secured to said leg portion while the outer ends of said straps and the fasteners carried thereby are disposed at the exterior of said leg portion.

In testimony whereof I have hereunto affixed my signature.

ANDREW NIEMI.
